UNITED STATES PATENT OFFICE

WILLIAM W. TUNIS, OF EASTON, MARYLAND.

IMPROVEMENT IN WORK-HOLDERS.

Specification forming part of Letters Patent No. **152,883**; dated July 7, 1874; application filed March 16, 1874.

To all whom it may concern:

Be it known that I, WILLIAM W. TUNIS, of Easton, in the county of Talbot and State of Maryland, have invented a new and Improved Combined Work and Spool Holder; and I do hereby declare that the following is a full, clear, and exact description of the same, reference being had to the accompanying drawing forming a part of this specification, in which—

Figure 1 is a sectional elevation. Fig. 2 is a top view.

The invention relates to that class of devices which are intended to facilitate the holding of ladies' work, so that it may be gradually and intermittently moved in an easy and convenient manner.

The invention will first be fully described in connection with all that is necessary to a full understanding thereof, and then pointed out in the claim.

A represents a knee-pad or piece of my device which hangs over the knee of the lady who uses the work-holder; and B a rod, by which it is connected with a head-piece, C, having the flange e, and containing, preferably, a needle or pin cushion upon the top thereof. D is a clamp fitting loosely about the rod B supported on a spiral spring, E, and

provided with arms d d, which embrace a table or stand, to which the work-holder is attached. F is a clamp-screw working in a thread of the lower arm d. G is a spool-holder, which may loosely surround the rod D and rest upon the piece A.

The application is as follows: The clamp D d being secured to a table or stand the lady presses lightly with her knee against the pad or piece A, thereby carrying the flange e above the upper arm d. She now inserts her work and proceeds with her operations, touching the piece A with her knee when and as often as she wishes to move her work along.

Having thus described my invention, what I claim is—

A work-holder, consisting of knee-pad A, rod B, head C, having flange e, clamp D, having arms d d, and the spring E, all arranged as described, to enable a person to unclose the holder by a slight movement of the knee, in the manner described.

The above specification of my invention signed by me this 2d day of March, 1874.

WM. W. TUNIS.
